TIME CLOCK

Benjamin Moss, Manitowoc, Wis.,

Application July 17, 1939, Serial No. 284,991

3 Claims. (Cl. 161—17)

This invention relates to time clocks designed primarily for use by chess players. Clocks heretofore employed have utilized two synchronized clock mechanisms with which is used a controlling member which acts upon the balance wheels of the respective clocks to stop or to release them. Not only are clocks of this type very expensive because of the kind of mechanism required and the care with which they must be balanced, but they also are objectionable because they quickly develop defects due to the abrupt stopping and starting of the balance wheel and because of the increased amount of mechanism employed.

An object of the present invention is to provide a clock designed primarily for use by chess players which has two dials and a set of hands cooperating with each dial but only employs a single clock mechanism, there being an intermediate mechanism of new and novel construction by means of which motion may be transmitted from the clock mechanism to the hands on either dial while the hands on the other dial are stationary.

A further object is to provide a means by which this intermediate mechanism can be actuated to operate the hands on either dial.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

In the accompanying drawings the preferred form of the invention has been shown.

40 In said drawings:

Figure 1 is a view partly in front elevation and partly in section of a clock embodying the present improvements.

Figure 2 is a horizontal section through the case of the clock and through the dials, the mechanism in the case being shown in plan.

Figure 3 is a section taken substantially on the line 3—3 of Figure 1, said section being enlarged and showing only a portion of the mechanism.

Figure 4 is a section on line 4—4 of Figure 3, parts being broken away.

Figure 5 is a section on line 5—5 of Figure 3.

Figure 6 is a section on line 6—6 of Figure 3.

55 Referring to the figures by characters of ref-

erence 1 designates a suitable case provided with two clock dials indicated at 2 and 3 respectively, there being associated with each clock dial an hour hand 4 and a minute hand 5.

A clock mechanism of the usual type is located in a housing 6 suitably supported within the case 1 and the main arbor 7 of the clock mechanism projects from housing 6 and through spaced plates or frame members 8 and 9 one of which is anchored to housing 6 as shown at 10. The 10 plates or frame members 8 and 9 are held together in spaced relation by bolts 11 and interposed sleeves 12 so as thus to form a rigid structure.

Arbor 7 is mounted, near its center, within 15 spaced gears 13 and 14, gear 13 being formed with a toothed extension 15 constituting a clutch member while another similar clutch member 16 is extended from the gear 14. These clutch members 15 and 16 are mounted for rotation within 20 the respective plates 8 and 9.

A spider 17 is mounted on arbor 7 between the gears 13 and 14 and is anchored to the plates 8 and 9 as shown at 18. Between this spider and plate 9 is supported a gear 19 which is in constant 25 mesh with gear 13. Another similar gear 20 is interposed between the spider and the other plate 8 and is in constant mesh with the gear 14. Gear 20 transmits motion through a train of 30 gears 21 to the arbors 22 and 23 of the hands 4 and 5 on dial 2 while another similar train of gears 24 transmits motion from gear 19 to the arbors 25 and 26 of the hands 4 and 5 on dial 3. These trains of gears are so proportioned that when either one of them is rotating, the hands 35 4 and 5 driven thereby will rotate at the proper ratio.

A guide 27 is extended from the housing 6 and is fixedly joined thereto. Mounted on this guide 40 is a slide 28 having spaced upwardly extending forks 29 and 30 movable therewith. Fork 29 extends into an annular groove 31 formed in a toothed clutch member 32 which is slidable on and rotatable with the arbor 7 where it can move 45 into and out of engagement with the clutch member 16. The forked member 30 is engaged in an annular groove 33 formed in a toothed clutch member 34 which is slidable on and rotatable with arbor 7 between the free end of said arbor 50 and the plate 9. This clutch member 34 is movable into and out of engagement with clutch member 15.

An actuating lever 35 is pivotally mounted at 55 and is connected at one end to one of the 55

forked members 29, as shown at 31. The other end of this lever is extended through an opening 36 in the guide 27 and thence through a cam slot 39 formed in a disk 40 which constitutes one 5 arm of a lever fulcrumed, near the periphery of the disk, on a fixed bracket 41, as indicated at 42. The other arm of this lever, indicated at 43, is pivotally connected at 44 to an actuating rod 45 which extends transversely of and is 10 slideable within the case 1. The ends of the rod project from the case and are provided with knobs 46.

A guide plate 47 is fixedly secured to bracket 41 and has a straight slot 48 therein through 15 which the lever 35 extends. A coiled spring 49 is seated in the bottom of case 1 and exerts a constant thrust upwardly against an enlargement or foot 50 at the lower end of lever 35.

The cam slot 39 is so proportioned that when 20 disk 40 is in an intermediate position, lever 35 is located in the center of said slot and also in the center of slot 48. At this time the lever is vertical or in direct line with spring 49 so that 25 said spring exerts a thrust longitudinally of the lever. Furthermore, when the parts are thus located, the two slideable clutch members 32 and 34 are out of engagement with the respective clutch members 16 and 15 so that motion will 30 not be transmitted from arbor 7 to either of the gear trains.

When it is desired to transmit motion to the hands on one dial from the clock mechanism, rod 45 is thrust in one direction so as to cause lever arm 42 to swing and produce a corresponding movement of the disk arm 40. The cam slot will thus operate to thrust lever 35 in one direction, this movement being accelerated by the spring 49 as soon as the spring and lever 35 are moved out of a dead center position. Consequently selected clutch member 32 or 34 will engage the adjacent gear clutch member so as to couple the same to arbor 7 and cause motion to be transmitted from the slot mechanism to the selected clock hands. The parts will remain 45 in this position until the rod 45 is shifted to its other extreme position whereupon lever 35 will be actuated to disengage the clutch member previously shifted into engagement and then engage the other clutch member so that motion will be transmitted from the arbor to the other 50 pair of clock hands. This movement likewise will be accelerated by the spring 49. When neither of the sets of hands is to be operated, the rod is pushed to an intermediate position so 55 as to bring the spring 49 and lever 35 into alignment as shown by full lines in Figure 3.

By providing a structure such as described, it becomes necessary to utilize only one clock mechanism, this being utilized to operate either of two 60 gear chains leading to the hands of the separate clock dials. Consequently the resultant structure is less expensive and less complicated than one

requiring two complete clock mechanisms and, furthermore, the mechanism is not caused to deteriorate because of sudden stopping and starting as occurs where the balance wheels are abruptly stopped by means heretofore devised. 5

What is claimed is:

1. A time clock including separate dials, hands movable on each dial, a train of gears for operating the hands on each dial, a clock mechanism including a main arbor, opposed clutch members 10 slideable on and rotatable with the arbor, and means under the control of an operator for shifting the clutch members to simultaneously couple the arbor to one train of gears and uncouple it from the other train of gears. 15

2. A time clock including separate dials, hands movable on each dial, a train of gears for operating the hands on each dial, a clock mechanism including a main arbor, opposed clutch members 20 slideable on and rotatable with the arbor, and means under the control of an operator for shifting the clutch members to simultaneously couple the arbor to one train of gears and uncouple it from the other train of gears, said means including connected members engaging and 25 adapted to operate the respective clutch members, a lever operatively connected at one end to the clutch engaging members, a pivoted actuating member having a cam slot through which one end of the portion of the lever extends, a 30 guide element having a straight slot crossing the cam slot and through which the lever extends, means under the control of an operator for shifting the actuating member to move the lever along the guide slot when subjected to 35 thrusts from one of the walls of the cam slot, and a spring exerting a constant tension against one end of the lever for holding said lever in either extreme position to which it may be shifted by the walls of the cam slot. 40

3. A time clock including separate dials, a pair of hands movable on each dial, a single clock mechanism including a main arbor, separate trains of gears normally uncoupled from the arbor for transmitting motion to the hands on 45 the respective dials, each train of gears including a gear in which the arbor is mounted to rotate, clutch members carried by the gears on the arbor and rotatable therewith, clutch members 50 slideably mounted on and rotatable with the arbor and shiftable into engagement with the respective gear clutch members, means embracing the trains of gears and engaging the respective shiftable clutch members for moving one of said members into engagement with a gear 55 clutch member and the other one out of engagement with the other gear clutch member, a shiftable actuating rod, means actuated thereby for moving the clutch shifting means, and a spring for holding the clutch shifting means yieldingly 60 in either extreme position.

BENJAMIN MOSS.
